(57) **CLAIM**

The ornamental design for a body fluid testing device, as shown and described.

DESCRIPTION

FIG. 1 is a perspective view of a body fluid testing device with the top closed showing my new device.

FIG. 2 is a rear view thereof.

FIG. 3 is a right side view thereof.

FIG. 4 is a left side view thereof.

FIG. 5 is a bottom view thereof.

FIG. 6 is a top view thereof.

FIG. 7 is a front view thereof.

FIG. 8 is a perspective rear view thereof with the top removed for clarity of the illustration.

FIG. 9 is a perspective view thereof with the top open.

FIG. 10 is a rear view thereof.

FIG. 11 is a right side view thereof.

FIG. 12 is a left side view thereof.

FIG. 13 is a bottom view thereof.

FIG. 14 is a top view thereof.

FIG. 15 is a front view thereof.

FIG. 16 is a perspective view thereof with the top open.

FIG. 17 is a perspective view thereof showing the upper side of the shell and the top open; and,

FIG. 18 is a perspective view thereof showing the bottom side of the shell and the top open.

The Shell member is separately shown in FIGS. 17 and 18 to show aspects of the design that may not be apparent in an assembled state.

1 Claim, 18 Drawing Sheets
